UNITED STATES PATENT OFFICE.

ANDREW J. BRADLEY, OF NEW YORK, N. Y.

ADJUSTABLE PRINTING-STAMP.

SPECIFICATION forming part of Letters Patent No. 770,956, dated September 27, 1904.

Application filed December 7, 1903. Serial No. 184,018. (No model.)

To all whom it may concern:

Be it known that I ANDREW J. BRADLEY, a citizen of the United States, and a resident of the city, county, and State of New York, have 5 invented a new and useful Improvement in Adjustable Printing-Stamps, of which the following is a specification.

My invention relates to printing-stamps; and its principal objects are to provide a stamp 10 which may be adjusted to print various words, numbers, and characters without removing any parts from the stamp or adding any parts thereto, to simplify and improve the adjustment and setting of type-wheels, to simplify 15 and improve the inking mechanism of stamps, and other objects hereinafter more fully appearing.

My invention consists in the parts and in 20 the arrangements and combinations of parts hereinafter described and claimed.

In the accompanying drawings, forming a part of this specification, and wherein like symbols refer to like parts wherever they occur, Figure 1 is a front view of my improved 25 printing-stamp, parts being broken away. Fig. 2 is a side view thereof. Fig. 3 is a rear view. Fig. 4 is a vertical sectional view, and Fig. 5 is a detail view of one of the radial arms.

30 The base-frame 1 of the stamp is substantially rectangular, and consists of a horizontal portion and vertical side portions terminating in laterally-extending feet 2 3, the lower ends of the side portions being tied together by rods 4 5.

Within the base-frame 1 a printing-frame 6 reciprocates. This frame is also substantially rectangular, and consists of a horizontal portion and vertical side portions. The side 40 portions have forwardly-extending integral brackets 7 8. A rod 9 is rigidly mounted in said brackets. A second rod 10 is rigidly mounted near the lower extremity of the side portions, and near the rear edge of the side 45 portions a third rod 11 is rigidly mounted. These rods, in addition to other functions, serve to tie the side portions together and stiffen the frame. The rod 10 projects through the side portions and into slots 12 13 in the 50 base-frame 1. The lower end of the print-

ing-frame is thus guided. A slotted tube 14, having a flange 15 at its lower end, is secured to the printing-frame near the center of the horizontal portion. It projects upwardly through a cylindrical part 16 on the horizontal portion of the base-frame. A stop-pin 17 is secured in the said cylindrical part and passes through slots 18 19 on opposite sides of the tube. At the top the tube 14 is screw-threaded to receive a knob 20. A spring 21 60 rests upon the stop-pin 17 and bears against the knob 20, and thus normally holds the printing-frame in its uppermost position. By pressure on the knob the spring may be compressed and the printing-frame may be lowered to its printing position.

Type-wheels 22 are rotatably mounted upon the rod 10, and adjusting-drums 23 are mounted upon the rod 9. The wheels and drums are arranged in pairs. As they are all alike, 70 the description of one pair will answer for all.

The type-wheel 22 is provided on its periphery with type. The latter may be of rubber, metal, or any other suitable material, and the characters may be letters, numbers, or any 75 other characters. A hub or pulley 24 projects laterally from the type-wheel and is preferably integral therewith. At one point of its periphery the hub is indented. A pin 25 projects from the type-wheel in register 80 with the indentation, there being space enough between the pin and the walls of the indentation to insert the driving-belt.

The adjusting-drum 23 is made preferably from sheet metal and consists of a disk having a laterally-projecting integral flange 26 extending almost around its periphery and a radially-extending integral arm 27. A narrow piece is stamped out of the disk and forms a pin 28. A spiral spring 29 is secured at one end to the rod 9 and at the other to the pin 28 on the drum. This spring serves to hold the drum securely in any position of adjustment. A belt 30, which may be made of any flexible material, but is preferably 85 made of wire, has one end secured near one of the free ends of the peripheral flange 26. It then passes part way round the drum 23, then around the hub 24 of the type-wheel 22, into the indentation under the pin 25, then 90

around the hub 24 again, and then around the other side of the drum 23 and is secured to the other free end of the peripheral flange 26. By this arrangement the type-wheel may be turned in either direction by means of the adjusting-drum. The belt being secured as it is to the hub, slipping is prevented.

An indicating-casing 31 is secured to the brackets 7 8 of the printing-frame 6. This casing is substantially a segment of a cylinder and is provided with a series of notched slots. There are as many slots 32 in the casing as there are type-wheels in the machine, and there are as many notches 33 on one edge 15 of each slot as there are characters on the corresponding type-wheel. Beside each slot the same series of characters 34 appear as are arranged upon the corresponding type-wheel. The radial arms 27 of the adjusting-drum extend 20 through the said slots 32, which are wide enough to permit lateral play of the former. Each arm has a projection 35 struck up upon the side adjacent the notched edge of its slot to engage the said notches 33. The arms being 25 resilient, the projection is disengaged when it is desired to move the arm by merely pressing it aside. Each arm is provided with a pointer 36, consisting of an integral L-shaped projection. The downwardly-extending branch is bent back at right angles to the forwardly-extending branch, thus bringing the pointer near the characters.

Brackets 37 38 project rearwardly from the base-frame 1. They are provided with slots 39 40, opening upwardly. On the outside of the side portions of the base-frame are secured retaining-springs 41 42, having holes registering with the lower ends of the slots 39 40, respectively. The upper edges of the springs 40 flare outwardly, so as to be easily pressed away from the frame. A rod 43 projects through said slots and the holes in the springs. This is the journal of the ink-roller frame. From it arcuate arms 44 45 extend downwardly and carry at their lower ends the ink-roller 46. A spring 47, doubled upon itself 45 at the center and having its branches coiled in opposite directions about the rod 43, engages a tie-rod 48 in the arcuate arms 44 45 50 with its free ends, while its center portion engages the rod 11 in the printing-frame. This spring holds the ink-roller in engagement with the type-wheels. When the type-wheels are pressed downwardly into printing position, the roller is moved aside, as indicated in dotted lines in Fig. 2. The action of the spring tends to move the rod 43 out of the slots 39 40, and hence the use of the retaining-springs.

In use the type-wheels may be set to print 60 different characters, and hence any desired combination of letters, numbers, and characters may be printed.

The device obviously admits of considerable modification within the scope of my in-

vention, and hence I do not wish to be limited 65 to the specific construction hereinbefore described. For example, while sixteen type-wheels have been shown more or fewer may be used. All the type-wheels have been shown as provided with letters of the alphabet; but 70 obviously part or all of the type-wheels could be provided with figures, or all of the wheels could be provided with both letters and figures or any combination of characters. The type-carrying members shown are type-wheels; but obviously type-belts could be substituted, the pulleys about which the type-belts run being rotatable type-carrying members just as type-wheels are. While the means for adjusting the type-wheels shown and described are preferred, it is obvious that gear-wheels could be substituted for the belt and pulleys or drums. Although the ink-roller has been shown and described as mounted in a pivoted frame, it is obvious that the same 85 end could be accomplished by mounting it in curved slots in the base-frame.

What I claim is—

1. A printing-stamp comprising a frame, an adjustable type-carrying member rotatably mounted therein, a sheet-metal adjusting-drum rotatably mounted in said frame and comprising a disk provided with an integral cylindrical flange and an integral radial adjusting-arm, and a belt connecting said drum and said type-carrying member, said belt being attached at its ends to said drum.

2. A printing-stamp comprising a frame, an adjustable type-carrying member rotatably mounted therein, a casing on said frame comprising an indicating-plate provided with a notched slot, a sheet-metal adjusting-drum rotatably mounted in said frame and comprising a disk provided with an integral cylindrical flange and a radial adjusting-arm, 100 said adjusting-arm having an integral pointer to coöperate with said indicating-plate, and a projection raised from said arm to coöperate with the notches in said slot, and a belt connecting said drum and type-carrying member.

3. A printing-stamp comprising a frame, a rotatable type-carrying member in said frame provided with a projecting hub rigid therewith, a drum rotatably mounted in said frame and provided with means to manipulate it, 115 and a belt connecting said drum and type-carrying member.

4. A printing-stamp comprising a frame, a rotatable type-carrying member in said frame provided with a projecting hub rigid therewith, a spring-tensioned drum rotatably mounted in said frame and provided with means to manipulate it, and a belt connecting said drum and type-carrying member and fixed to one of them to prevent slip.

5. A printing-stamp comprising a frame, a rotatable type-carrying member in said frame provided with a projecting hub rigid there-

with, a rod mounted in said frame, a drum rotatably mounted on said rod and provided with means to manipulate it, a spring connected at one end to said rod and at the other end to said drum, and a belt connecting said drum and said type-carrying member and fixed to both.

6. A printing - stamp comprising a base-frame, a printing - frame reciprocatingly mounted therein, a type-carrying member in said printing - frame, rearwardly - extending brackets on said base-frame provided with upwardly-opening slots, leaf-springs upon said brackets, respectively, provided with openings in alignment with each other and said slots, a rod mounted in said slots and extending through said springs, and a spring-pressed ink-roller mounted on said rod and arranged to be moved out of the path of the type-carrying member by the downward movement of the latter.

7. A printing - stamp comprising a base-frame, a printing - frame reciprocatingly mounted therein and provided with a transverse rod, a type-carrying member in said printing-frame, an ink-roller frame pivotally mounted on said base-frame and provided with an ink-roller and a spring bearing at one end upon said transverse rod and at the other end

upon said ink-roller frame to press said ink-roller upon said type-carrying member.

8. A printing - stamp comprising a base-frame, a printing - frame reciprocatingly mounted therein, a series of adjustable type-carrying members in said printing-frame, a like series of spring - tensioned adjusting-drums, and a like series of belts connecting said type-carrying members and drums respectively.

9. A printing - stamp comprising a base-frame, a printing - frame reciprocatingly mounted therein, a series of independently-adjustable type - carrying members in said printing - frame, a like series of independently - movable adjusting means operatively connected to said type-carrying members, respectively, and each comprising a drum and belt secured thereto at its opposite ends and means to retain said type-carrying members in predetermined positions of adjustment.

In testimony whereof I have signed my name to this specification in the presence of two subscribing witnesses.
